IGNITION DEVICE

Application filed May 19, 1930. Serial No. 453,555.

This invention relates to improvements in ignition devices for multicylinder internal combustion engines.

The object of the present invention is to provide a simplified ignition device having a minimum number of parts, thereby substantially reducing production costs.

Further objects and advantages of the present invention will be apparent from the following description, reference being had to the accompanying drawings, wherein a preferred embodiment of one form of the present invention is clearly shown.

In the drawings:

Fig. 1 is a diagrammatic view showing the ignition device and its circuit connections.

Fig. 2 is a longitudinal sectional view of the condenser unit of the ignition device.

Fig. 3 is a graphic view showing the relative time of circuit making and breaking intervals of the two circuit interrupters of the ignition device.

Referring to the drawings, the ignition device is shown comprising a casing 20, which insulatingly supports two terminals 21 and 22. A drive shaft 23 is rotatably supported by the housing 20, said drive shaft having a cam 24 provided thereon, said cam having a plurality of lobes 25.

Within the casing 20 there are provided two circuit interrupters, one having the contact arm 26, the other the contact arm 27. These contact arms are insulatingly, pivotally supported by posts 28 and 29 respectively.

Contact arm 26 carries a contact 30 and contact arm 27 has the contact 31 provided thereon. One end of a resilient blade or spring 32 is attached to the contact arm 26 by a rivet 33, which also secures the wearpiece 34 to said contact arm. The other end of this spring conductor 32 is in electrical connection with the terminal post 21.

From the foregoing it may be seen that spring conductor 32 not only electrically connects the contact arm 26 with the terminal 21, but it also urges said contact arm so that its wearpiece 34 engages the cam 24. A spring conductor 35 has its one end secured to the contact arm 27 by the rivet 36, which also secures the wearpiece 37 to said contact arm.

Like in the other circuit interrupter, spring conductor 35 electrically connects arm 27 to the terminal post 22 as well as urging said arm so that its wearpiece 37 engages the cam 24. Two stationary contacts 38 and 39 are provided within the housing 20, these contacts being grounded to the housing 20 as at 40. Contact 38 is adapted to be engaged by the contact 30 on arm 26 when the wearpiece 34 on said arm is intermediate the lobes 25 of the cam 24. When the wearpiece 37 of the arm 27 rides between the cam lobes 25 then the contact 31 on said arm may engage the stationary contact 39.

It will be noted in Fig. 1 that the contact arms 26 and 27 are so arranged relatively angularly that when the wearpiece of one is riding on one of the cam lobes to cause contact disengagement, the wearpiece of the other contact arm will be riding between the cam lobes to maintain contact engagement, and thus one circuit interrupter is always closed while the other is disengaged.

The ignition device includes a distributor unit 45 having a plurality of terminals 46 connected to the proper spark plugs 47 of the engine, not shown. A central, high tension terminal 48 on the distributor unit is connected with the rotor 49 while another high tension terminal 50 is in communication with a circular track 51 in the distributor unit which in turn is in electrical connection with the rotor 52.

The ignition device also includes a pair of ignition coils, one having the primary winding 53 the other the primary winding 54. A secondary winding 55 is associated with the primary winding 53 of one ignition coil, while the secondary winding 56 is provided in the ignition coil having the primary winding 54. Both these primary windings 53 and 54 are connected with a storage battery 57 through the wires 58 and 59. The secondary winding 55 is connected with the high tension terminal 50 of the distributor unit through the wire 60, the wire 61 connecting the secondary winding 56 with the high tension terminal 48 of the distributor unit.

From this it may be seen that sparking impulses from the coil including windings 53

and 55 are directed to the high tension terminal 50 and rotor 52 of the distributor unit, while sparking impulses from the coil including wires 54 and 56 are directed to the terminal 48 and rotor 49 of the distributor unit. The primary winding 53 is also connected with the terminal post 21 through the wire 62, while the primary winding 54 of the other ignition coil is connected to the terminal post 22 through the wire 63.

10 A condenser 65 has two wires 66 and 67 leading therefrom, one wire being connected to the insulated terminal 21 through the wire 62, the other wire 67 of the condenser being connected to the insulated terminal post 22 through the wire 63.

15 Referring to Fig. 2, the condenser is shown comprising a shell or casing 70 in which convolutions of metallic foils 71 and 72 are provided. These convolutions of two metallic foils are properly separated by layers of insulating material such as paper and designated by the numeral 73, the assembly of the two foil sheets and their separating sheets of 20 paper being in tubular form about a hollow core 74. One foil has its edges exposed at one end of the condenser as at 75, while the other foil has its edges exposed at the opposite end of the condenser as at 76. Wire 66 25 extends through an opening in the end of the case toward the opposite end of the condenser and has its end electrically engaging the foil edge 76. Wire 67 extends through an insulating end cover 77, the wire being 30 in electrical connection with the foil edges 75 at the opposite end of the condenser. Thus it may be seen that no part of the condenser is grounded, for wire 66 connects the one foil while the wire 67 connects the other foil, 35 these wires 66 and 67 in turn being connected to insulating terminal posts 21 and 22 carried by the ignition device housing.

40 In the operation of this device, however, alternate sides of the condenser are grounded through a circuit interrupter. For instance, if the ignition device is in the position as shown in Fig. 1, the battery will discharge through the wires 59 and 58, primary coil 54, wire 63 to terminal post 22, then through 45 the spring conductor 35, arm 27, across contacts 31 and 39 to the ground 40 and back through the battery via the ground connection 40. The current flowing through this 50 primary coil 54 will energize the same and when the cam 24, rotating in the direction of the arrow on said cam in Fig. 1, causes its lobe 25 to engage wearpiece 37 and move arm 27 so that its contact will move out of 55 engagement with the contact 39, the arm 26 will have been moved so that its contact 30 will be in engagement with the stationary contact 38 before interruption of the contacts 31 and 39 will have taken place. Interruption 60 of the circuit through the primary winding 54 will cause a sparking impulse from

the secondary winding 56 to be directed through the wire 61, terminal 48, thence through the rotor 49 to the proper terminal 46 and spark plug 47. The contacts 30 and 38 being closed at the time of the circuit 65 interruption of contacts 31 and 39, condenser 65 will have its one wire 67 in connection with the performing circuit including the wire 63 while the other wire 66 of the condenser will be grounded through wire 62, 70 terminal 21, conductor spring 32, arm 26, contacts 30 and 38, ground 40 back to the ground of the battery. When the circuit interrupter including arm 26 and contacts 30 and 38 is moved to interrupt the circuit, the 75 other interrupter including contacts 31 and 39 will be closed and thus the wire 66 of the condenser 65 will be connected to the performing circuit, while wire 67 of the condenser will be grounded through the interrupter including contacts 31 and 39.

80 From the foregoing it may be seen that a single condenser may be so constructed and arranged as to operate properly with two separate and distinct interrupters, said interrupters acting alternately, one as a circuit interrupter the other as a cooperating grounding device for the condenser.

85 While the form of embodiment of the present invention as herein disclosed, constitutes a preferred form, it is to be understood that other forms might be adopted, all coming within the scope of the claims which follow.

90 What is claimed is as follows:

1. An ignition device for a multi-cylinder, 100 internal combustion engine comprising, in combination, an engine operated cam having a plurality of spaced lobes; insulatingly pivoted levers each having a wear piece, said levers being so arranged that the wearpiece 105 of one is between the cam lobes when the wearpiece of the other is engaged by one of the cam lobes; a contact on each lever, a terminal for each lever; a resilient conductor between each terminal and lever respectively, 110 said resilient conductor urging the respective lever so that its wear piece engages the cam and electrically connecting the respective lever with a terminal; a grounded stationary contact for each lever adapted to be 115 engaged by the contact on the respective lever; and a condenser connected between the terminals.

2. An ignition device for a multi-cylinder, 120 internal combustion engine comprising, in combination, a housing; two terminal posts insulatingly carried by said housing; an engine driven cam having a plurality of cam lobes; a pair of contact levers pivotally supported within the housing and insulated 125 therefrom; stationary contacts carried by the housing and adapted to be engaged by the respective contact levers; wearpieces on the respective contact levers which are so arranged relative to the cam so that the wear 130

piece of one lever is between the cam lobes to cause engagement of its respective contact lever and its cooperating stationary contact when the wearpiece of the other lever is engaged by a cam lobe to cause disengagement of its contact lever and the cooperating stationary contact; spring conductors connected between each terminal post and contact lever, urging the lever toward the cam and electrically connecting it with the terminal post; and a condenser connected between the two terminal posts.

3. An ignition device for a multi-cylinder, internal combustion engine comprising, in combination, an operating member; two circuit interrupters adapted to be operated alternately by said operating member, each interrupter comprising an insulated movable contact and a stationary grounded contact; and a condenser connected between the two movable contacts, said condenser comprising alternate layers of a metallic foil and insulating sheets, alternate edges of the foil extending from opposite ends of the condenser, and wires, one of which is connected to the foil extending from one end of the condenser and to the insulated contact of one interrupter, the other wire being connected to the foil extending from the other end of the condenser and to the insulated contact of the other interrupter.

4. An ignition device for a multi-cylinder, internal combustion engine comprising, in combination, an operating member; two circuit interrupters adapted to be operated alternately by said operating member, each interrupter comprising an insulated movable contact and a stationary grounded contact; and a condenser connected between the two movable contacts, said condenser comprising a shell, an assembly of alternate layers of a metallic foil and insulating sheets, the alternate foils extending from the opposite ends of the assembly, and wires each connected with a group of foils extending from the respective ends of the assembly said wires extending from the condenser shell ends and being connected to the insulated contacts of the respective circuit interrupters.

5. An ignition device for a multi-cylinder, internal combustion engine comprising, in combination, an operating member; two circuit interrupters adapted to be operated alternately by said operating member, each interrupter comprising an insulated movable contact and a stationary grounded contact; and a condenser connected between the two movable contacts, said condenser comprising a shell; a tubular coil of convolutions of two sheets of a metallic foil each separated by a convolution of paper, the one foil having its edges exposed at one end of the coil the other foil at the opposite end of the coil, wires extending through the tubular coil one connected at one end to the exposed edges of the

one foil and at the other end to the insulated contact of one circuit interrupter, the other wire connected at the other end to the exposed edges of the other foil and at its other end to the insulated contact of the other circuit interrupter. ⁷⁰

In testimony whereof I hereto affix my signature.
